UNITED STATES PATENT OFFICE.

PHILIP FERBER, OF HOBOKEN, NEW JERSEY, ASSIGNOR TO THE KEUFFEL & ESSER COMPANY, OF HOBOKEN, NEW JERSEY, A CORPORATION OF NEW JERSEY.

TELESCOPE.

1,137,192.

Specification of Letters Patent. Patented Apr. 27, 1915.

Application filed February 1, 1913. Serial No. 745,613.

To all whom it may concern:

Be it known that I, PHILIP FERBER, a citizen of the United States, residing at Hoboken, in the county of Hudson and State 5 of New Jersey, have invented certain new and useful Improvements in Telescopes, of which the following is a specification.

This invention relates to bore-sight telescopes or telescopes designed to assist in 10 bringing the bore of a gun of large caliber adjusted to a point exactly on a distant target, and its novelty consists in the construction and adaptation of the parts, as will be more fully hereinafter pointed out.

15 To attain the end sought for, the line of sight through the telescope must be brought exactly parallel to the axis of the bore of the gun with which it is to be used. For this purpose the telescope is removably and 20 temporarily mounted in some suitable manner in the breech of the gun. A centering point is attached to the gun at or near the muzzle for instance, formed by cross wires in a framework removably inserted in the 25 gun, and when the cross wires of the telescope bisect this centering point the line of sight of the telescope should be parallel to the bore of the gun, so that when the telescope is sighted on the distant target the 30 line of sight of the gun should be exactly in line with this target provided, of course, the telescope is in proper adjustment. In order to secure such proper adjustment it is necessary that means should be provided 35 for moving the cross wires in the telescope in both a vertical and horizontal direction and also means for revolving the telescope upon its longitudinal axis. To that end it is necessary that the adjusting screws for 40 the cross wires should be within reach of the operator at all times, and provision should be made for revolving the telescope in a truly cylindrical bearing, the axis of which is coincident with the longitudinal 45 axis of the telescope. Furthermore, provision should be made for focusing all objects at different distances because, if the telescope is only capable of being focused on a distant object, the centering point at 50 the muzzle of the gun cannot be distin-

guished; and on the contrary if it is only capable of being focused on a near object, for instance, on the centering point at the muzzle of the gun, the distant target cannot be properly distinguished.

I have, in the invention which is the subject matter of this application, endeavored to overcome the objections heretofore existing in instruments of this class and have fulfilled the requirements which I have outlined as necessary to a proper accomplishment of the object sought. The invention includes a telescope comprising an inner tube containing the lenses and an outer sleeve with two intermediate bearings between them, one a spherical bearing and another a truly cylindrical bearing in line with the spherical bearing. Also, a system of cross wires arranged in an eye-piece tube slidably movable within the main tube 65 of the telescope, and means for adjusting such cross wires, and further means for adjusting the inner tube of the telescope with respect to its outer sleeve and maintaining it in position after such adjustment.

In the drawings, Figure 1 is a side elevation of a telescope embodying the invention; Fig. 2 is a longitudinal central section thereof; Fig. 3 is a side elevation of the device, a portion being cut away to 70 show concealed parts; Fig. 4 is a transverse section on the plane of the line 4-4 in Fig. 1, and Fig. 5 is a section similar to that shown in Fig. 4 but exhibiting four screws instead of two.

In the drawings, 10 is the usual tube of a telescope provided at one end with an objective indicated at 11 and at the opposite end with an eye-piece indicated at 12, 12, 12, 12, the different lenses being carried in a 90 tube 120 mounted to slide in a sleeve 121 also within the tube 10 by means of a ring 122, and a terminal collar 123 mounted against the outer side of said ring 122.

Loosely mounted to surround the tube 10 95 for a substantial portion of its length is a cylindrical sleeve 13 expanded by a shoulder 130 to form an annular flange 131 terminating in a ring 132 provided with both external and internal threads. A second cy- 100

2

lindrical sleeve 14 also surrounds the tube 10 and at a slight distance therefrom, and being threaded at one end to engage the ring 132, is rigidly secured to the sleeve 13 5 by such threaded connection. The sleeve 14 is provided with a series of radially arranged adjusting screws 140 and a holding member 141 constantly pressed inward by a spring 142 arranged in a tubular casing 143 10 threaded into the sleeve 14. There may be two adjusting screws 140 as indicated in Fig. 4, or four or more adjusting screws as indicated in Fig. 5.

The tube 10 is provided with two annular bearings 15, 15, having outer spherical surfaces. It is also provided with a cylindrical collar 16, the outer surfaces of which are exactly parallel to the longitudinal axis of the telescope, and which collar is arranged 20 in the zone of the set screws 140 of the holding piece 141. An annular portion of the tube 13 indicated at 133 is adapted to bear against one of the bearings 15 and an intermediate annulus 134 threaded into the flange 25 131 of this tube 13 is adapted to bear against the other of the bearings 15.

It is obvious that when the adjusting screws 140 are moved the tube 10 as a whole will be moved within the tube made up of 30 the two cylindrical sleeves 13 and 14 as a whole but always moved upon the spherical bearings 15, 15, and adjustable in any direction permitted by the movement of the set screws 140 which are so arranged as to 35 provide for such movement in every desired direction.

The tube 120 of the eye-piece is provided 40 near its outer extremity with cross wires 17 held in position by adjustable threaded members 170, and this tube 120 is slidably mounted within a second tubular member 125, its movement being limited by means of a stop member indicated at 126.

It will be observed that the sleeve 13 is 45 externally threaded and there is provided an annular nut 18 which is adapted to be placed over this sleeve and to move along the same. This threaded sleeve and nut in connection with the shoulder 130 on the 50 sleeve 13 is intended as a means for mounting the telescope within the bore of the gun. This is accomplished by means of a temporary framework inserted transversely within the bore of the gun and having a central 55 annulus, the inner periphery of which is threaded to engage the external threads of the sleeve 13. This transverse frame is the usual form of means for mounting the telescope within the gun, and no further description of it is needed to those skilled in the art.

The manner of using the device is as follows: The telescope is inserted in the transverse frame and the nut 18 is adjusted to

hold it firmly in position. The gun is provided with a centering point, usually established at the muzzle, as before stated, by means of a ring inserted at the muzzle having cross wires or other indicator at the center of the bore. Such centering point 65 having been inserted and the telescope having been placed in the temporary frame above referred to, the telescope is then pointed at this central point and revolved in its longitudinal axis, and the adjusting 70 screws 140 resting against the cylindrical bearing 16 are manipulated until the line of sight of the telescope remains truly pointed on the centering point at the muzzle of the gun. In Fig. 3 there is illustrated the 75 manner in which the manipulation of the screws 140 will relatively move the telescope tube and its sleeve. The bore of the gun is then in a true line of collimation with the line of sight of the telescope. The telescope can then be sighted at any distant point as a target, and when so sighted the bore of the gun is in true line with the target, and the eye-piece can be focused on such distant point by sliding the tube 120 in or out until 80 90 the image is sharply defined.

What I claim is:

1. A telescope comprising a tube having an objective in one end, a sleeve in the other end, an eye piece slidable in the sleeve and having cross wires, means for limiting the sliding movement of the eye piece in the sleeve, and means for supporting the telescope and laterally adjusting the same in the bore of a gun. 95

2. A telescope comprising a tube provided at one end with an objective and at the opposite end with a slidable eye-piece carrying cross wires which move with it, a sleeve adapted to surround the tube, a spherical bearing intermediate the tube and the sleeve, a cylindrical bearing on the outside of the tube arranged between the spherical bearing and the cross wires, and adjusting means for moving the sleeve and tube relatively and in a direction transverse to their longitudinal axes. 105

3. A telescope comprising a tube provided at one end with an objective and at the opposite end with a slidable eye-piece carrying cross wires which move with it, a sleeve adapted to surround the tube, a spherical bearing intermediate the tube and the sleeve, a cylindrical bearing on the outside of the tube arranged between the spherical bearing and the cross wires, and means carried by the sleeve and adapted to coöperate with the tube to move the sleeve and tube relatively and in a zone transverse to their longitudinal axes, and which means include adjusting screws threaded into the sleeve and impinging upon the cylindrical bearing. 115

4. A telescope comprising a tube provided

at one end with an objective and at the opposite end with a slideable eye-piece carrying cross wires which move with it, a sleeve surrounding the tube, a universal joint between the sleeve and tube, a cylindrical bearing on the outside of the tube, and adjusting screws threaded onto the sleeve and impinging upon the cylindrical bearing to move the sleeve and tube relatively and in a zone transverse to their longitudinal axes. 10
In testimony whereof I affix my signature in presence of two witnesses.

PHILIP FERBER.
